US0D1054094S

(12) **United States Design Patent** (10) Patent No.: **US D1,054,094 S**
(45) Date of Patent: ** Dec. 10, 2024

(54) **VAPORIZER DEVICE**

(71) Applicant: **JUUL Labs, Inc.**, San Francisco, CA (US)

(72) Inventors: **Brandon Cheung**, San Francisco, CA (US); **Steven Christensen**, Burlingame, CA (US)

(73) Assignee: **JUUL Labs, Inc.**, Washington, DC (US)

(**) Term: **15 Years**

(21) Appl. No.: **29/813,993**

(22) Filed: **Nov. 2, 2021**

(51) **LOC (14) Cl.** **27-07**

(52) **U.S. Cl.**

USPC **D27/162**

(57) **CLAIM**

The ornamental design for a vaporizer device, as shown and described.

DESCRIPTION

FIG. 1 is a top, front, and right side perspective view of a vaporizer device of our design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The dash-dash broken lines illustrate portions of the vaporizer device that form no part of the claimed design.

The dash-dot broken lines illustrate boundary lines that form no part of the claimed design.

1 Claim, 5 Drawing Sheets
